CLAIM

The ornamental design for a forend with mounting rails, as shown and described.

DESCRIPTION

FIG. 1 is a top isometric view of a forend incorporating our new design;

FIG. 2 is a bottom isometric view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof; and,

FIG. 8 is a back elevation view thereof.

The broken lines shown in the drawing Figures are meant to illustrate environment and form no part of the claimed design.
